INVENTOR,

Peter V. Husted.

BY

Dr P. Preble Jr
his ATTORNEY,

UNITED STATES PATENT OFFICE.

PETER V. HUSTED, OF NEW YORK, N. Y.

WIRE.

SPECIFICATION forming part of Letters Patent No. 398,259, dated February 19, 1889.

Application filed October 5, 1888. Serial No. 287,272. (No model.)

To all whom it may concern:

Be it known that I, PETER V. HUSTED, a citizen of the United States, and a resident of the city, county, and State of New York, have 5 invented certain new and useful Improvements in Wire, of which the following is a specification.

The object of my invention is to produce a new kind of spirally-threaded wire, in which 10 the spiral is made as nearly as practicable parallel with the length of the wire. This thread may be a projecting surface running like a spiral ridge along the wire, or it may 15 may be cut out or depressed.

15 In the accompanying drawings, Figure 1 represents the wire with raised or projecting thread. Fig. 2 is a longitudinal section of the die through which the wire has to be drawn to make it of the shape shown in Fig. 1. Fig. 20 3 represents the wire with the thread cut into its surface.

Same letters indicate similar parts in the different figures.

25 *a* is the body of the wire, and is round in cross-section.

b is the spiral thread, which is made as nearly as practicable parallel with the length of the wire.

30 *e* is the die, provided with the cylindrical channel *d* and with the thread-cutting channel *c*. When wire like Fig. 3 is to be made, the channel *c* becomes a ridge and cuts the thread instead of raising it.

Common cylindrical wire, somewhat larger 35 in cross-section than body *a*, is drawn through

the die *e* in the usual method of drawing wire, and in its passage through said die is forced to take the form shown in Fig. 1 or Fig. 3, according as channel *c* is raised or depressed in the die.

40 By "usual" way I have reference to such drawing-machines as that described in Patent No. 364,126, dated May 31, 1887, and granted to W. A. McCool, and other well-known types of that class in which a grip carried on a carriage 45 seizes the wire and retreats, drawing the same through the die. The only change necessary to draw my improved wire on such machines, as will be readily understood by those acquainted with the art of drawing metals, 50 would be to have the grip mounted with anti-friction bearings, so that the grip might revolve slowly as it retreats in unison with the twist of the wire, and thus relieve the latter from all strain caused by drawing. Of course 55 the grip is not allowed to retreat to a great distance from the die before it lets go and is returned to get a new hold.

55 The uses and advantages of my improved wire are, I think, sufficiently obvious, both for 60 making wire nails and spikes, and for other purposes, not to require further explanation.

I claim—

65 A spirally-threaded wire in which the thread is made nearly parallel with the length of the wire, substantially as shown and described.

PETER V. HUSTED.
